EXTENSIBLE DROP-LEAF TABLE

Lars G. Larson, Chicago, Ill.

Application June 29, 1949, Serial No. 101,991

2 Claims. (Cl. 311—52)

1

This invention relates to an extensible table and it is an object of the invention to provide an improved table of this character.

Extensible tables conventionally employ one or more independent leaves, drop leaves, or pull-out leaves. All of these devices for increasing the area of a table top have their individual disadvantages. The independent or separate leaves are awkward to handle and storage space must be provided therefor when they are not in use. The use of such leaves also requires a split table top, at least one portion of the top being slidable with respect to the base of the table. This inherently results in an unstable construction. Drop leaves are undesirable because they prevent the use of the one or more edges of the table when they are in their hanging or inactive position. Drop leaves are also subject to being marred when not in use because of their vulnerable position. Pull-out leaves have none of the disadvantages of the independent or insertable leaf or the drop leaf, but are notoriously unstable and, because of the necessarily complex structure associated therewith, add considerably to the cost of manufacturing a table.

According to this invention, extension leaves are linked to the table in such a way that they may swing from a position overlying a main table top to a position alongside thereof. The simple linkage provided for this purpose causes the finished surface of the leaves to be always uppermost whether the leaves are in their folded or extended position. The table top thus formed is very rigid whether in the folded or extended position, it presents no storage problem, it is economical to manufacture, and all sides of the table may be used whether the table is in its folded or extended position. An extension leaf so arranged is sufficiently rigid that in accordance with one embodiment of this invention a drop leaf is mounted on the outer edge of the extension leaf whereby the table top can be expanded still further. In accordance with one specific embodiment of this invention, the table top is made rotatable with respect to the base or frame of the table whereby the base, normally disposed underneath the main portion of the table top, can be made to extend outward and support the extension leaves.

Accordingly, it is another object of this invention to provide an extensible table which is inherently stable.

It is another object of this invention to provide an extensible table, all sides of which are available for use whether the table is in its folded or extended position.

2

It is another object of this invention to provide an extensible table having leaves which are stored as a part of the table when not in use.

It is another object of this invention to provide an extensible table in which extension leaves are linked to the table for movement between positions overlying a fixed table top and positions alongside the fixed table top.

It is another object of this invention to provide an extension leaf for a table, such leaf being linked to the table for movement between a position overlying a fixed table top and a position alongside the table top.

It is another object of this invention to provide an extension leaf for a table, one surface of such leaf being always uppermost whether such leaf is in its folded or unfolded position.

It is another object of this invention to provide an extensible table, having extension leaves of the character described, in which the table top is rotatable with respect to the table frame whereby the frame can be made to support the extension leaves.

It is another object of this invention to provide an extension leaf having a drop leaf connected thereto.

It is another object of this invention to provide an extension leaf for a table, such leaf having the various advantages stated above while being simple, rugged and economical.

30 This invention, together with further objects and advantages thereof, will best be understood by reference to the following description taken in connection with the accompanying drawing, and its scope will be pointed out in the appended claims.

In the drawing, in which like parts are designated by like reference numerals:

Fig. 1 is a plan view of a table illustrating one embodiment of this invention;

Fig. 2 is an elevation view of the same table shown in a partially extended position;

Fig. 3 is an elevation view of the same table in another partially extended position; and

45 Fig. 4 is an enlarged cross-sectional view taken along the line 4—4 of Fig. 1, showing one form of linkage for an extension leaf in accordance with this invention.

The table shown in the drawing has a main, relatively fixed table top portion 11, a pair of extensions 12, and a pair of drop leaves 13, all supported on a base structure 14. The leaves 12 are connected to the fixed table top 11 by links 15, each of these links being pivotally connected at one end to the fixed portion 11, preferably at 55 the edge adjacent the lower surface thereof, as

may be plainly seen in Fig. 4. The other end of each link 15 is pivotally connected to the extension leaf 12, preferably at the lower surface thereof.

It will be readily apparent that the extensions 12 may move by virtue of the links 15 between a position atop the fixed portion of the table top 11, as illustrated in Fig. 2 and in dotted lines in Fig. 4, and a position immediately adjacent the fixed portion 11, as illustrated in Figs. 1 and 3 and by the solid lines in Fig. 4. In the latter position, the upper surfaces of the fixed portion 11 and the leaves 12 lie in the same plane. It will also be apparent that the surface of the leaf 12 to which the link 15 is connected will always be lowermost whether the leaf is in its folding position, as in Fig. 2, or its extended position, as in Figs. 1 and 3. Accordingly, only one surface of the leaf 12 need be finished, this surface always being uppermost.

The link 15 is bent to form a horizontal leg 15a and a vertical leg 15b so that the link can extend up over the edge of the fixed portion 11 when the extension leaf is in the folded position. The link may be connected to the fixed portion at a point, for example, halfway up the vertical edge thereof. The vertical leg 15b need then be only half as long as the thickness of the table top, the length of the leg 15b required to clear the fixed portion being determined by the distance of the pivotal connection from the top surface of the center portion.

If two extension leaves 12 are employed, it is desirable that when the leaves are in their folded position, their inner edges abut and that their outer edges extend to or beyond the edges of the fixed top portion 11, as seen in Fig. 2. In this case, it will be apparent that the length of the horizontal leg 15a of the link should equal approximately one quarter of the width of the fixed top portion 11. A single extension leaf may also be used, and in this case the width of the leaf should be equal to or slightly greater than the width of the fixed top portion and the length of the horizontal leg 15a should be approximately one-half of the width of the fixed top portion.

When the leaf 12 is in its folded position, it rests securely upon the central portion 11, strips of felt or other soft material preferably being secured to the lower surface of the leaf in order to prevent marring of the upper surface of the fixed portion 11. The sides of the fixed portion 11 and the inner edges of the extension leaves are preferably beveled in the manner shown in Fig. 4 in order that the leaves may move to their extended positions without striking the upper edges of the sides of the fixed top portion.

According to the embodiment illustrated, the entire table top may be revolved 90 degrees about a pin 14a such that the long dimension of the lower table structure 14 extends outward beyond the longitudinal sides of the fixed table top portion 11. This action is diagrammatically illustrated in Fig. 1 in which the two positions of the lower table structure 14 are shown in dotted lines A and B. When the base structure 14 is in the position designated as B in Fig. 1, it serves as a solid support for the leaves 12 in their extended position. The rotatable table top is not a necessary feature of this invention and ordinary pull-out brackets or swinging brackets may be used to support the leaves 12.

Whether the leaves 12 are supported by brackets or by the base table structure 14, they are inherently so secure and are so situated that

drop leaves 13 may be connected thereto for further extension of the table top.

When the base 14 is in the position designated by the letter A in Fig. 1, and the extension leaves are in their folded positions, the drop leaves 13 can be supported by any suitable brackets such as swinging brackets 16 attached to the longitudinal sides of the base. The brackets 16 must lie entirely below the lower surface of the center portion 11, at least when the brackets are in their folded position, in order that they will not interfere with the movement of the extension leaves to their extended positions or with the rotation of the table top with respect to the base. In view of this and since the lower surface of the drop leaf 13 lies in the same plane as the upper surface of the center portion 11, as may be seen in Fig. 2, it is desirable to employ spacers such as cleats 13a attached to the lower surface of the drop leaves as this will permit the bracket to support the drop leaves at the proper level while swinging about a vertical axis. Alternatively the cleats may be omitted and the brackets 16 arranged to move slightly upwardly as they swing to their outward extending position as shown by the phantom lever in Fig. 2.

The drop leaves may alternatively be supported by the ends of the base 14 when the extension leaves 12 are folded and when the base is rotated with respect to the table top to the position designated B in Fig. 1. It is apparent then that either the extension leaves 12 or the drop leaves 13 may be supported by either the ends of the table base 14 or by the brackets 16.

When it is desired to extend the table top to its maximum length, the base is preferably rotated to the position designated by the letter B to support the extension leaves 12, and a second set of brackets such as pull-out brackets 17, mounted on the ends of the base 14, are employed to support the drop leaves 13. Where a non-rotatable table top is used, a telescoping bracket or other suitable bracket may be arranged to extend outward of the longitudinal edges of the base 14 to support the extension leaves or the drop leaves, or both.

It will be apparent that the extension leaves 12 have numerous advantages over the various conventional extension leaves. When the leaves are in their folded position, the present no storage problem as they are located immediately above the fixed table portion 11. When the leaves are in either this folded position or in their extended position all sides of the table are available for use and the leaves are inherently very stable since in the folded position they rest directly on the fixed table portion 11 and in the extended position they rest flatly on either the rotated base portion 14 of the table or on brackets of any desired form. No complex linkage or table construction is necessary as is the case in a conventional pull-out leaf. Since the extension leaf 12 is inherently stable, it is practical to hinge a drop leaf thereon in order to obtain still further extension of the table top, the drop leaves hanging down over and concealing the edges of the center portion when the table top is in its folded position.

The preferred embodiment, in which the table top is rotatable and in which drop leaves are hinged to the extensions 12, has a particular advantage in that it provides particularly rigid support for the leaves 12 whereby the latter may more securely support the drop leaves, with the brackets for supporting the drop leaves being

connected to the base portion 14 of the table immediately adjacent the hinged edge of the drop leaf.

While particular embodiments of the invention have been shown, it will be understood, of course, that the invention is not limited thereto since many modifications may be made, and it is, therefore, contemplated to cover by the appended claims any such modifications as fall within the true spirit and scope of the invention.

The invention having thus been described, what is claimed and desired to be secured by Letters Patent is:

1. In an extensible table, a rectangular central top member, an extension leaf, a drop leaf, a rectangular table base for supporting said central member and said leaves, and a link connecting said extension leaf to such table for movement of said extension leaf between a first position overlying at least a portion of said central member and a second position alongside said central member, one surface of said extension leaf being uppermost in both of said positions and one edge of said extension leaf abutting a longitudinal edge of said central member when in said second position, said drop leaf being pivotally connected to a second edge of said extension leaf opposite said abutting edge, said base being rotatable with respect to said central member about a vertical axis between a normal position and a rotated position displaced 90° from said normal position, said base when in said normal position being entirely covered by said central member and the ends of said base extending outward of the longitudinal edges of said central member when said base is in said rotated position, one of said ends of said base when in said outward extending position being adapted to support said extension leaf in said second position and being adapted to support said drop leaf when said extension leaf is in said first position, said base having an extendible bracket at said one end of said base, said bracket being adapted to support said drop leaf when said base is in said rotated position and said extension leaf is in said second position.

2. In an extensible table, a rectangular central top member, an extension leaf, a drop leaf, a rectangular table base for supporting said central member and said leaves, and a link connecting said extension leaf to such table for movement of

said extension leaf between a first position overlying at least a portion of said central member and a second position alongside said central member, one surface of said extension leaf being uppermost in both of said positions and one edge of said extension leaf abutting a longitudinal edge of said central member when in said second position, said drop leaf being pivotally connected to a second edge of said extension leaf opposite said abutting edge, said base having an extendible bracket adjacent said longitudinal edge thereof, said bracket being adapted to support said extension leaf in said second position and to support said drop leaf when said extension leaf is in said first position, said base being rotatable with respect to said central member about a vertical axis between a normal position and a rotated position displaced 90° from said normal position, said base when in said normal position being entirely covered by said central member and the ends of said base extending outward of the longitudinal edges of said central member when said base is in said rotated position, one of said ends of said base when in said outward extending position being adapted to support said extension leaf in said second position and being adapted to support said drop leaf when said extension leaf is in said first position, said base having an extendible bracket at said one end of said base, said bracket being adapted to support said drop leaf when said base is in said rotated position and said extension leaf is in said second position.
